SALES AND DISPLAY TICKET

Raymond G. Hanson, Crystal Lake, Ill., assignor
to Wells Lamont Corporation, Chicago, Ill., a
corporation of Minnesota

Application August 21, 1953, Serial No. 375,795

1 Claim. (Cl. 40—2)

1

This invention relates to a sales and display ticket of the type used on pairs of gloves and the like to hold the gloves together and to provide a surface whereon advertising and trademark indicia may be displayed. More particularly, this invention relates to a sales and display ticket which is adapted to not only secure the paired gloves or the like together, but which also is adapted to act as a supporting means or link between the pair of gloves or the like and a fixed supporting surface in display windows, or counters, etc.

In the past it has been common practice in the glove industry, as well as other industries in which such articles as socks are manufactured, to separate manufactured gloves into pairs and affix to each pair a label on which the glove size is indicated. The label may also conveniently carry other indicia, such as advertising, the manufacturer's trade-mark and a space for marking the sales price. The glove labeling operation in the past has been a hand stapling operation but recently machines have been developed which greatly reduce the labor and cost of affixing labels to gloves. One such machine is that disclosed in the application of Hans F. Trepte, Serial No. 341,501, filed March 10, 1953. By using such a machine the gloves are easily stapled together in pairs using only a single label; the gloves are so secured to each other that they are not readily detachable, and yet one of gloves may be tried on by a customer. The present invention is an improved sales and display ticket or label adapted for use in such a machine, and which also greatly facilitates the display of the finished gloves when in the hands of the retailer.

It is frequently more desirable to display clothing and the like from fixed supports at different elevations in the display area, rather than spread the clothing on a table top or display window floor, which, for instance, may comprise the display area, since only a relatively few items may be displayed on a table top or display window floor while the space above such table top or floor allows a maximum number of items to be displayed. Efforts have been made to conveniently display items of clothing of the type which normally are sold in pairs, such as pairs of gloves and the like, at different elevations in a display space, but it has been found that the number of ways of display is limited by the fact that such items cannot be readily supported or suspended in the space provided for display without some wear and pos-

2

sible damage to the clothing resulting from contact with supporting surfaces where the clothing is hung directly on such a surface, or from the process of securing string, cord or pins to the clothing whereby the clothing may be suspended from a fixed supporting surface. One possible solution has been to package gloves or the like and to secure the supporting means to the package. This solution has its disadvantages since the packaging process materially increases the cost of the gloves or the like and the customer cannot try the gloves or the like on without destroying or damaging the package.

Therefore, it is an object of this invention to provide a sales and display ticket or label which not only secures gloves and the like together in pairs, but also provides a means whereby the gloves may be suspended or supported in a display area from a fixed supporting surface such as a display stand rod or the like.

It is a further object of this invention to provide a sales and display ticket or label which is adapted to secure the paired gloves together in such a manner that a customer may try one of the gloves on without scratching himself on the sharp ends of the securing staple and without accidentally pulling the paired gloves apart.

It is yet another object of this invention to provide a sales and display ticket or label which is so proportioned that when it is secured to the paired gloves or the like, adequate space is provided on the outside surface of the ticket for advertising, price and trade-mark indicia.

It is yet a further object of this invention to provide a roll of sales and display tickets or labels which is particularly adapted to aid the manufacturer in rapidly pairing gloves, socks, stockings and the like.

In accordance with the present invention, I provide a sales and display ticket or label for pairs of gloves and the like comprising an elongated, substantially flexible, rectangularly shaped member formed with a bend line spaced preferably slightly from the transverse center thereof to provide a relatively long leg and a relatively short leg. The member is adapted to be bent about the bend line into a substantially U-shaped configuration and the ends thereof are adapted to be secured to a pair of gloves or the like. Preferably, the longer leg or portion resulting from the U-shaped configuration is secured to the outside surface of one of the gloves or the like and the shorter leg or portion is secured inside the cuff of the other glove or the

like, the respective legs or portions being secured to each other through the gloves by a securing device such as a staple. The ticket or label is formed in said short leg or portion with a perforated flap adjacent the bend line and the flap is adapted to be bent about said bend line, upwardly from the plane of said short portion or leg to an upstanding position. I provide frangible means for holding the flap in the plane of the ticket until its use is desired, and when it is desired to support the paired gloves or the like, it is merely necessary to grasp the end of the flap and pull gently to break the frangible means, and then the perforated portion of the flap may be disposed in a position to receive a fixed supporting surface such as a display stand rod or the like.

From the foregoing, it will be obvious that the present invention provides substantial advantages over prior practices. For instance, pair gloves may be supported or suspended at different elevations in a display space by the same label or ticket that secures them together and without any damage to the gloves. This ticket allows more gloves or the like to be displayed in a particular display space and yet is a relatively inexpensive way of securing pair gloves or the like together; use of the ticket results in a considerable improvement over older methods of displaying gloves and the like, such as by packaging them and then suspending or supporting the package from a fixed supporting surface.

In addition to the foregoing, it is an object of the present invention to provide a sales and display ticket which is economical of manufacture, convenient in use, capable of ready attachment to paired gloves or other clothing and which readily lends itself to modern mass production methods.

Other objects and advantages of the present invention will become apparent in the following description of a preferred embodiment of the sales and display ticket of the present invention and the preferred use thereof.

Now, in order to acquaint those skilled in the art with the sales and display ticket of the present invention, I shall describe, in connection with the accompanying drawings, a preferred embodiment of the ticket and the manner of using same.

In the drawings:

Figure 1 is a side elevation view of a stapling machine, such as that disclosed in the aforementioned Hans F. Trepte application, in which my improved sales and display ticket is adapted to be used;

Figure 2 is a plan view of a preferred embodiment of my present invention;

Figure 3 is a cross-sectional view substantially along line 3—3 of Figure 1;

Figure 4 is a front elevational view of a pair of gloves suspended from a rod type support by means of my improved sales and display ticket; and

Figure 5 is a rear elevational view of the same pair of gloves shown in Figure 4.

Referring now to the drawings, reference numeral 10 generally indicates a typical specimen of the preferred embodiment of my sales and display ticket or label, and reference numeral 12 generally indicates a stapling machine in which said ticket or label is adapted to be affixed to pairs of gloves or the like, though it is to be understood that my ticket could readily be stapled to gloves and the like by hand if so desired. Referring to Figure 2, the preferred embodiment of

my invention comprises a rectangular, substantially flexible body member 14 having a bend line 16 formed therein spaced preferably slightly from the transverse axis of the ticket to provide a relatively short leg and a relatively long leg for the purpose hereinafter made clear. The body member is said to be substantially flexible, since it is a thin sheet or paper, and therefore may be flexed without difficulty. However, the paper material is of a relatively stiff composition, the stiffness of which tends to maintain all parts of the body member in the same plane until the body member is bent by hand or by a stapling machine, such as the one illustrated in the drawings. Bend line 16 is formed in the body member 14 so that the body will bend immediately at the most desirable point when a pressure is applied to the body normally of its flat surfaces, but the stiffness of the paper is such that the ticket will remain flat even though some pressure moves it in the plane of the ticket, as for instance, when the ticket passes through the hereinafter described machine. The bend line comprises a line of small perforations as shown in the preferred embodiment, but it may be formed in any other convenient manner which produces like results. Each ticket 10 is formed with a flap 18 having a perforation 20 at the center thereof and a semi-circular peripheral edge 22 which merges into the straight line edges 24 and 26. The flap 18, as may be seen, is preferably formed by a generally U-shaped cut, although other shaped cuts, and configurations of the flap, are permissible. As shown in the preferred embodiment, the edges 24 and 26 preferably end at the bend line 16 so that the flap is bendable about the bend line. The flap 18 is detachably retained in the plane of the body member 14 by the frangible portions 28 and 30, which, in the embodiment illustrated, are portions of the body member 14 left uncut by the tool that cuts the edges 22, 24 and 26 in the body member, thereby forming the flap 18. The flap 18 may assume other shapes, if so desired, but I have found the illustrated shape most satisfactory.

It is to be noted that two frangible portions are used in the present embodiment and are located on either side of the center of flap 18; while the frangible portions 28 and 30 may be located at other positions along the edge of the flap, I prefer to locate them as shown since when the ticket is bent along bend line in one of the hereinafter described manners, the centermost point 21 of the peripheral edge 22 projects slightly upwardly from the body of the ticket, making it much easier for one to grasp the flap to break the frangible means. I comprehend that one frangible means could be substituted for means 28 and 30, if so desired, and said single frangible means might be located at point 21. Moreover, other types of frangible means may be employed to hold the flap detachably in place without departing from the scope of my invention.

As shown in Figure 2, the bend line 16 defines the ticket or label 10 into a relatively long portion 17 and a relatively short portion 19, with the flap 18 being formed in the short portion in such a manner that the point on the peripheral edge 22 spaced furthest from the bend line 16 does not extend half the distance between the bend line 16 and the end (edge 13) of the short portion, all for purposes hereinafter made clear.

I prefer to form a plurality of tickets in a long strip of paper material with the trade-mark and other indicia applied, where possible, so that they

may be conveniently stored in rolls until needed, and conveniently handled when applied to gloves or the like either by hand or by a stapling machine.

As aforesaid, reference numeral 12 generally indicates a stapling machine which will expeditiously affix my ticket or label to gloves or the like, and a brief description thereof is included so that the importance of the structural features above described will be made clear. The machine comprises an elongated bar 32 supported by legs 34 which may be fixed to a suitable table 36 or the like. Secured to bar 32 at the rear of the machine is an arm 38 which pivotally mounts a roll 40 comprising a strip 42 of tickets 10 for use in the stapling operation. A stapler head 44 is pivotally mounted on pin 46 carried by the angle plates 48 and 50, the said angle plates being secured to the bar 32 immediately forward of the arm 38. A spring 52 acts between the stapler head 44 and a bar 54, fixed between the angle plates 48 and 50 and spaced above the bar 32, to aid in returning the stapler head to inactive position as hereinafter made clear. Extending forwardly of angle plates 48 and 50, and on each side of the bar 32 are the thin plate members 56, 58 and 60, 62. Extending rearwardly of the angle plates 48 and 50 are the similar thin plate members 64, 66 and 68, 70. The thin plate members are so mounted as to define a passageway through which the strip of tickets 42 passes through the machine.

As shown more particularly in Figure 3, the upper thin plates 56, 60, 64 and 68 are somewhat wider than lower plates 58, 62, 66 and 70 and provide guide means for retaining the strip 42 within the passage defined by the lower thin plate members. The angle plates 48 and 50 are spaced apart the same distance that the lower plate members are to allow the ticket strip 42 to pass between them.

Located forwardly of the thin plate members 56, 58, 60 and 62 is the die member 72 having a slot 74 therethrough which is of the same width as the distance between the lower thin plate members. An elongated groove 76 is formed in bar 32 at the center thereof and extends from the point 78 (see Figure 3) at the rear of the machine to the front edge of the die member 72. Bar 32 is further formed with a rectangular space 80 immediately in front of the die member 72, and also with a tongue shaped guide member 82 at the front of the machine. A fork shaped flipper member 84 is pivotally mounted at 85 to the forward edge of space 80, a vertically moving cutting blade 86 is pivoted to the forward edge of die member 72 and a staple die 88 is affixed to bar 32. Pivotally mounted in depending arm 90 (see Figure 1) is the shaft 92 having the segmental gear 94 and the operating lever 96 carrying handle 98 affixed thereto. The segmental gear 94 engages the rack 100, the upper portion of which is slidable in the groove 76. Pivotally mounted in the upper portion of the rack 100 is the spring biased pawl 102 which carries the forwardly projecting face 104, said pawl being biased to move in a clockwise direction as viewed in Figure 1. Suitable springs 106 are provided to bias the rack 100 toward the rear of the machine, where the rear end of the rack member bears against the end 78 of groove 76.

The strip 42, with the indicia bearing surface facing downwardly, passes down around roller 108 and into the passageway defined by thin plates 66 and 70, angle plates 48 and 50, thin

plates 56, 62 and the slot 74 in the die member 72, the bar 54 being spaced sufficiently above bar 32 to allow the strip to pass therebeneath. The various elements of the machine are so proportioned that when the pawl 102, carried by rack 100, is in its rearmost position (shown in Figure 1), the upwardly biased face 104 of pawl 102 has entered the perforation 20 in one of the tickets 10 of the strip 42 disposed immediately above it. Handle 98 is then pulled forwardly, and the strip 42 is moved forwardly over the space 80 to the point where leading edge 11 has passed over the staple die 88. The handle 98 may then be released or moved rearwardly so that the pawl 102 will move rearwardly to its original position, with face 104 leaving the perforation 20 and moving back to position shown in Figure 1. At this point in the operation of the machine, one ticket has been indexed or positioned for stapling to a pair of gloves or the like.

The operator then picks up a pair of gloves 108, places them in a side-by-side relationship, with palms of each glove abutting. He then grasps them with both hands 110 and 112, as shown in Figure 3, with the fingers of each hand underneath and the thumbs on top, the thumbs pulling back and opening the cuff of the upper glove. The operator then places his hands and the gloves immediately adjacent the guide member 32 so that his index fingers will contact the side surface of the guide member, with the gloves 108 being held just above the upper surface thereof. The gloves are positioned over the staple die 88 and over the leading edge 11 of leading ticket 10 by the operator pushing his hands away from him with his fingers following the said side surfaces until the leading portions of his index fingers are stopped by the safety stops 114 and 116. By stepping on a suitable foot treadle (not shown) the operator downwardly actuates a movable frame 118 whereupon, by means of suitable linkages, the cutting blade 86 detaches the leading ticket 10 along its trailing edge 13, the flipper member 84 bends the ticket 10 along bend line 16 to move the short portion 19 against and within the open cuff and over the staple die 88 and the stapler head is lowered against the ticket 10, the cuffs of gloves 108 and the staple die 88 to throw a single staple, for instance staple 119 in Figures 4 and 5, through both ends of the ticket and the portions of the gloves lying therebetween. The resilient arm 117 on the stapler head 44 pushes the short portion 19 of the ticket into engagement with the inner surface of the upper glove cuff. Upon releasing the foot treadle, springs, indicated generally at 120, together with spring 52 and cutting blade spring 121, return the parts to their original positions for the next stapling operation. The gloves are then removed from the machine, paired and completely stapled.

In arriving at the illustrated design of the ticket or label 10, a number of factors were taken into consideration. First of all, the material used had to be sufficiently stiff so that when the face 104 of pawl 102 contacted the leading portion of perforation 20, the strip 42 would move forwardly in the machine and would not be torn or be crumpled about bend line 16 and entangled in the passageway. Moreover, the bend line 16 had to be located in such a manner that a sufficient amount of outwardly facing surface (that is, the surface facing outwardly of the outer surface of the cuff of the lower glove and bearing against the staple die 88 when the gloves are in stapling position), is provided so that the necessary ad-

vertising, sales and trade-mark indicia may be applied to and/or be visible on the label. The bend line 16, located as shown in Figure 2, provides the relatively long portion 17 which abuts the outer surface of the adjacent glove cuff (see Figure 4), and a relative short portion which abuts the inner surface of the glove cuff immediately adjacent to it (see Figure 5). The perforation 20 had to be so located that the ticket, when indexed for the stapling operation, would be positioned in such a manner that the bend line 16 would lie just behind or rearwardly of the lower cuff of the pair of gloves being stapled, so that the shorter portion 19 of the ticket would be inserted, by the bending function of fork member 84 and the later pressing function of the resilient arm 117, a sufficient distance within the open cuff of the upper glove to position the trailing edge 13 of the ticket somewhat forwardly of the staple die 88. The flap 18 had to be formed in the body of the ticket in such a position that it would not interfere with the stapling operation and would leave sufficient room at the ends of the ticket for receiving the staple. Moreover, the flap had to be located in a portion of the ticket which did not bear indicia and it had to be provided with sufficient frangible means to hold it in the plane of the ticket during the indexing operation and until the perforation was needed to suspend the pair of gloves from a display stand or the like. I have found that the structural arrangement illustrated in Figure 2 is most satisfactory for stapling machines such as that hereinbefore outlined, and also lends itself well to occasions where hand stapling of gloves or the like is desirable. Other structural arrangements will be immediately comprehensible to those skilled in the art, however, without departing from the scope of the invention.

While the ticket 10 is adapted for use in the above described stapling machine, or in other similar types, it will be obvious to those skilled in the art that the ticket may be stapled to the outside surfaces of both cuffs of a pair of gloves, if this is found desirable. Moreover, the ticket may with equal facility be applied to socks, stockings or to types of clothing which does not necessarily come in pairs.

It will also be obvious to those skilled in the art, after a perusal of this specification, that the ticket may readily be applied by hand to gloves and the like or other clothing. The ticket is first bent into a U-shaped configuration and the legs of the U are passed over the article to be labeled, a hand staple or other attaching device may then be used to secure the ends of the legs to the article. Manifestly, bend line 16 may be omitted, if so desired, whether the label is used in a stapling machine such as that described or is applied to the goods by hand; moreover, the bend line 16 could be located at the middle of the ticket, if so desired, or elsewhere. However, it is advantageous to have the bend line 16 at some point in the ticket since one can always be sure that the label will bend immediately and neatly at a predetermined place. It is to be noted that if the bend line 16 is located at a point other than that shown, the illustrated machine would have to be adjusted so that when the leading ticket is indexed for the stapling operation, the bend line will be located just behind or rearwardly of the cuff of the lower glove or the like being stapled.

Referring now to Figures 4 and 5, the manner in which flap 18 may be utilized to support the

pair of gloves stapled together by the hereinbefore described stapling machine will be described. In Figures 4 and 5, there is shown one type of support from which the pair of gloves 108 may be suspended which comprises a horizontal rod 122, fixed to a suitable support (not shown), and which has an upwardly angled front end 124. To suspend or support the paired gloves from rod 122, it is merely necessary to pull the rounded edge 22 upwardly from the plane of the short portion 19 so as to break the frangible portions 28 and 30, and then move the ticket and gloves so as to pass the rod through the perforation 20. The gloves will then hang as shown in Figure 4, with the longer portion, having the sales, advertising and trade-mark indicia thereon, facing outwardly, or toward the direction in which the customers will be standing or passing. As shown in Figure 5, the flap 18 extends upwardly from the ticket 10 and the gloves, and a sufficient portion of the short portion remains adjacent the inner surface of the gloves to place a limited amount of advertising, sales or trade-mark indicia, if so desired. The number of gloves which may be supported by the rod 122 is limited only by the strength and length of the rod, and in a particular display area a number of rods 122 may support different selections or sizes of gloves at different elevations. While the bend line for the flap 18 could be located at a point spaced from the bend line 16, I prefer to have the flap bend line coincide with bend line 16 as one perforation operation forms both; moreover, less strain is exerted on the relatively narrow shoulders formed when the flap is in use.

It is to be noted that when the ticket 10 is applied as shown in Figures 4 and 5, the centermost portion of the rounded periphery 22 (point 21) will project outwardly slightly from the short portion 19 of the ticket due to the positioning of frangible means 28 and 30 in the preferred embodiment. The edge of the flap 18 is therefore readily grasped by one desiring to separate the frangible means to suspend the gloves or the like from a support such as rod 122.

The foregoing description and the drawings are given merely to explain and illustrate my invention, and the invention is not to be limited thereto, except in so far as the appended claim is so limited, since those skilled in the art who have my disclosure before them will be able to make modifications and variations therein without departing from the scope of the invention.

I claim:

A combined securing, suspension and price ticket for a pair of gloves or the like comprising a non-rigid unitary strip of tough flexible paper or the like, generally rectangular in shape and folded on a laterally extending line to form a folded ticket having a pair of generally parallel legs, one of said legs being a short leg for insertion within the open end of a glove and the other leg being a long leg lying along the outer margin of the other glove to provide a label and price marking area, said legs and gloves being adapted to be secured together by means of a staple extending through and connecting said legs together and adapted to pass through the gloves adjacent their open upper ends, a cut in one leg providing an integral flap from within the leg, said cut being substantially U-shaped and being interrupted by connecting frangible means which are disposed on either side of the longitudinal center of said flap whereby, when the ticket is folded and said legs are bent into generally par-

allel relationship, the tip of the flap tends to rise from the plane of its leg so that it may be more easily grasped, a hinge line for the flap, said flap, when the ticket is folded, being adapted to be swingable along with the leg from which it is formed to a position not in the plane of the other leg, but said flap being adapted, when the frangible means is broken, to be swung around its hinge line, at the option of the user, from said last named position to a position substantially in the plane of the other leg, said hinge line for the flap coinciding with the fold line of the ticket, and said flap having a round hole substantially

centrally thereof for accommodating a generally horizontal rod from which the ticket may support the gloves which it secures together.
